(57) **CLAIM**

The ornamental design for a cord stopper, as shown and described.

DESCRIPTION

FIG. 1 is a front elevational view of a cord stopper of the claimed design;

FIG. 2 is a back elevational view of the cord stopper of FIG. 1;

FIG. 3 is a top view of the cord stopper of FIG. 1;

FIG. 4 is a bottom view of the cord stopper of FIG. 1;

FIG. 5 is a left-side view of the cord stopper of FIG. 1;

FIG. 6 is a right-side view of the cord stopper of FIG. 1; FIG. 7 is a cross-sectional view taken on line 7—7 of FIG. 1;

FIG. 8 is a cross-sectional view taken on line 8—8 of FIG. 2;

FIG. 9 is a perspective view of the cord stopper of FIG. 1; and,

FIG. 10 is an environmental view with the broken line showing of a jacket being for illustrative purposes only and forming no part of the claimed design.
